UNITED STATES PATENT OFFICE.

WILLIAM M. VENABLE, OF PITTSBURGH, PENNSYLVANIA, ASSIGNOR TO BLAW-KNOX COMPANY, A CORPORATION OF NEW JERSEY.

EXCAVATING-BUCKET.

1,258,833.

Specification of Letters Patent. Patented Mar. 12, 1918.

Application filed December 7, 1917. Serial No. 205,911.

To all whom it may concern:

Be it known that I, WILLIAM M. VENABLE, a citizen of the United States, residing at Pittsburgh, in the county of Allegheny and State of Pennsylvania, have invented certain new and useful Improvements in Excavating-Buckets, of which the following is a specification.

This invention relates to excavating buckets, and more particularly to the "clam shell" type of bucket which commonly consists of a pair of hinged scoop segments supported at their outer corners and adapted to be opened and closed by lowering or raising the main or bucket hinge and operated automatically by a single operating line or cable or adapted to be opened by a trip line controlled by the operator.

This invention has for its principal objects, the provision of a bucket that may be operated entirely by a single line, that is, a bucket that may be closed to receive a charge, elevated and its contents dumped and another charge taken by manipulation of one operating cable which supports the bucket; the provision of a bucket that may be caused to open and discharge its contents by a manually operated trip line if desired; the provision of a simple effective folding link carrying the lower sheave whereby, when folded, it will be held in folded position by the weight of the bucket and which may, without the use of any latches and triggers, be unfolded to lower the bucket hinge to open the bucket simply by shifting the position of the link so that the weight of the bucket will pull it open; the provision of a bucket having a lower sheave having two relative supporting positions with respect to the bucket hinge so that the bucket may be dropped away from the lower sheave to open the bucket, the said means for holding the sheave in either relative position requiring no latches or triggers and therefore will operate and function properly regardless of wear; the provision of a bucket wherein the lower sheave will lie to one side of the upper parts of the bucket when open, so that a hook or block secured to the overhead support may clear all parts and may be lowered close to the lower sheave in case the cable loop is close to the sheave; and such other objects as may hereinafter appear. One embodiment of the

invention is illustrated in the accompanying drawings, wherein—

Figure 1 is a side elevation of the bucket in its wide open position as it would appear with the bucket resting upon the earth and the cable slackened; Fig. 2 is a side elevation of the bucket in the act of being closed by a pull on the cable—the scoops have just partially closed; Fig. 3 is a side elevation of the bucket showing the parts in closed position; Fig. 4 is a side elevation of the bucket showing the position of the parts after the bucket hinge has been lowered while the bucket is suspended, caused by the unfolding of the folding link carrying the lower sheave; and Fig. 5 is an end elevation of the bucket when the scoop segments are in extreme open position shown in Fig. 1, but with the lower sheave block shown in its raised position.

Referring to the drawings, the bucket apparatus comprises a pair of scoop segments 1 and 2 pivoted together by a hinge 3. The outer corners of the segments or scoops 1 and 2 are supported by corner bars 4 and 5, respectively, which are pivoted at their lower ends to the scoop by pins 6 and 7, respectively. The upper ends of the bars are pivotally joined by means of the corner bar pivot 8.

Referring to Fig. 5, it will be seen that the corner bars are pivoted to each side of the scoop segments and are held in spaced relation adjacent their upper ends by a sheave block support 9 which is securely bolted to the corner bars 5. This support carries a sheave block 10, to which is pivoted for rotation, a pair of sheaves 11. The support also carries a pair of downwardly projecting sheave stops 12 adapted to arrest the upward movement of a lower sheave, to be hereinafter described.

It will be seen, by reference to the drawings, that if the corner bars are supported, the bucket may be opened by lowering the bucket hinge 3, and may be closed by raising the bucket hinge.

The bucket is operated by a pair of cables 13 spaced apart so that they will prevent the bucket from rotating upon the cables as an axis, but in operation and effect they are the same as a single cable and will hereinafter be treated as such. A single line can readily be used by simply at-

taching a tag line to the bucket at any convenient point so that rotation of the bucket will be prevented by the line.

A lower sheave block 14, carrying two pairs of sheaves 15, is pivoted to the bucket hinge 3 by a folding link consisting of a curved supporting link 16 pivotally connected at one end to the hinge 3, and a locking link 17 hinged at one end to the free end of the link 16 by a link pivot 18. The free end of the locking link 17 carries the sheave block 14, the center of which, when the folding link is folded, lies against the curved portion of the supporting link 16 at 15 19, (see Figs. 1, 2 and 3) so that its center lies to the right of the plane of the hinge 3 and the link pivot 18. Therefore, if the block is raised, it will be held adjacent the hinge by the folding link which will remain in folded position because the hinge pivot 18 will remain on the left side of the plane of the lower sheave center and the bucket hinge 3. Referring to Fig. 3 it will be seen from the above that the folding link is held in folded position by the weight of the bucket when the lower sheave 15 is supported without the aid of any special latches, levers or triggers which would become worn and fail.

30 The orbit of the lower sheave 15 is determined with respect to a point on the scoop segment 2 by a pair of radius rods 20, pivoted at one end to the corner bar pivots 7 and at the other end to the lower sheave shaft 21. These rods will cause the folding link to always fold by gravity and move the sheaves 15 to the position shown in Fig. 1 when the bucket is resting upon the ground in open position. It will be seen 40 that the sheaves 15, when in lowermost position, lie to one side of the bucket hinge and are not directly under the corner bar pivot 8. Therefore, a block may be lowered from a crane and the hook thereof fastened 45 to the loop 13 without interference with the corner bar pivot 8.

The cable 13 is reeved down around a sheave 15, up and around a sheave 11 and down around the under side of a second 50 sheave 15 and thence to an anchor clip 22 which is secured to the scoop segment 2. The cable is fastened to the clip 22 at 23, which point is intermediate the outer corner of the scoop segment and the hinge 3. The purpose of securing the cable at this 55 point is to limit the downward movement of the bucket hinge 3 when the sheave 15 is supported in the position indicated in Fig. 4, and the folding link unfolded.

60 Stops 24 are secured to each scoop segment to limit the downward opening of the bucket when the scoop segments are resting upon the ground as illustrated in Fig. 1, but in order to avoid shock to the bucket ele-

ments when the hinge 3 is suddenly dropped 65 by the unfolding of the folding link, the cable 13 is secured at a point between the outer scoop support 7 and the hinge 3 so that the downward movement is arrested before the stops 24 come in contact. 70

When the bucket has been closed by the hoisting of the cable 13 the parts will occupy the position shown in Fig. 3, the upward movement of the sheave 11 being arrested just short of contact with the sheave stop 12 by the contact with one another of the digging edges of the scoop segments. It will be seen that the bucket hinge 3, and the lower sheave pivot 21, are in the same plane while the folding link pivot 18 lies to the left of that plane. It will also be seen that the folding link cannot be unfolded without moving the link pivot 18 to the right of the plane of the hinge 3, and the sheave pivot 21. To accomplish the movement of the link pivot 18 to the right past the said plane, it is necessary to prevent movement of the sheave pivot 21 to the right. This is accomplished by the radius bar 20. The link pivot may be moved to the right by two methods; first, the bucket may be lowered to the earth so that it will rest in closed position. Further slackening of the cable will permit the folding lever to fall toward the right of the hinge 3 because the center of gravity of the folding link is to the right of the said hinge. After the folding lever has shifted so that the link pivot 18 lies to the right of the sheave pivot 21, pulling up of the cable will unfold the folding link and cause the bucket to open and discharge its load. Second, the folding link may be unfolded while the bucket is suspended above the earth by means of a trip lever 26 pivoted to the corner bars 5 by the pivot pin 27. This lever carries at one end a downwardly projecting trip arm 28 which is normally held in the position indicated in Fig. 3, by reason of the greater weight of the trip lever 26. If the trip lever 26 is normally raised, by the 100 pulling of any suitable connecting means, the trip arm 28 will engage the folding link adjacent the link pivot 18 and move it to the right of the sheave pivot 21. The weight of the bucket will immediately pull the link pivot 18 to the right still farther and unfold the link causing the bucket to open rapidly. As previously stated, the shock will be absorbed by the cable by reason of its connection with the bucket segment between the outer support 7 and the bucket hinge 3. 105

In some cases it is desirable to open the bucket automatically by manipulation of the operating cable alone, in which case the first described method of opening is employed. In other cases it may not be expedient to lower the bucket to open it, so the trip lever 110 115 120 125

26 is provided so that the bucket may be readily opened without lowering, by operating a trip line.

The complete operation of the bucket is 5 as follows. Assuming that the bucket is wide open and resting upon the ground as shown in Fig. 1, it will be seen that all parts occupy the position shown by reason of the effects of gravity and that the hinge 3 is 10 limited in its downward movement because the stops 24 are in engagement. Thus the hinge and sheaves are held out of contact with the earth to be excavated. Pulling upward on the cable 13 will cause the hinge 3 15 to be raised and the scoop drawn together and at first the parts will occupy the position indicated in Fig. 2. Finally the bucket will be closed, and the parts will occupy the position illustrated in Fig. 3. If the trip 20 lever 26 is then operated to move the hinge pivot 18 to the right of the sheave pivot 25, the weight of the bucket will unfold the link and discharge the load, and the parts will assume the position shown in Fig. 4. 25 The stop 12 then prevents further upward movement of the sheave 15 by reason of its engagement with the stop.

If the bucket is then lowered to the earth again the radius rod 20 will cause the block 30 14 and sheaves 15 to fall toward the left the instant the scoop segments touch the ground and the cable is slackened. The downward movement of the block 14 and the movement toward the left will cause the 35 folding link to fold and the parts will again be brought to the position illustrated in Fig. 1 by the force of gravity. When the folding link has been closed it is automatically locked against unfolding and pulling 40 on the cable will again first raise the bucket hinge 3 to close it and then hold the bucket closed while the bucket is being raised. The cycle of operation may then be repeated.

In the event that the bucket is to be operated entirely by the operating cable without the use of a trip line, after the bucket has been filled, its contents may be dumped by lowering the closed bucket upon the ground and playing slack to the cable. The 45 50 folding link will then fall to the right in the manner previously described and automatically unlock the folding link. Subsequent pulling up of the cable will open the bucket and discharge the load and the parts 55 will occupy the position shown in Fig. 4. The bucket may then be lowered to receive another load.

It is obvious that many changes may be made in the details of the construction without departing from the spirit of the invention and the invention is not limited to the specific structure herein disclosed.

What I claim is:

1. An excavating bucket comprising in

combination, a pair of scoop segments, a 65 hinge for joining the segments so that they may be opened and closed by vertical movement of the hinge, a cable for supporting the hinge, and a folding link connecting the cable with the bucket hinge adapted when 70 folded and supporting the bucket hinge to be held in folded position by the weight of the bucket and to be unfolded by weight of the bucket to lower the hinge when the link elements are relatively displaced a predetermined distance. 75

2. An excavating bucket comprising in combination, a pair of scoop segments, a hinge for joining the segments so that they may be opened and closed by vertical movement of the hinge, a cable for supporting the hinge, a folding link connecting the cable with the segment hinge adapted when folded and supporting the bucket hinge to be held in folded position by the weight of 80 the bucket and to be unfolded by the weight of the bucket to lower the hinge when the link elements are relatively displaced, and means for relatively displacing the link elements. 85

3. An excavating bucket comprising in combination, a pair of scoop segments, a hinge for joining the segments so that they may be opened and closed by vertical movement of the hinge, a cable for supporting the hinge, and a folding link connecting the cable with the bucket hinge adapted when folded and supporting the bucket hinge to be held in folded position by the weight of 90 the bucket and to be unfolded by weight of 95 the bucket to lower the hinge when the link elements are unfolded a predetermined distance. 100

4. An excavating bucket comprising in combination, a pair of scoop segments, a hinge for joining the segments so that they may be opened and closed by vertical movement of the hinge, a cable for supporting the hinge, and a folding link having a joint, connecting the cable with the bucket hinge adapted when folded and supporting the bucket hinge to be held in folded position by the weight of the bucket, with the joint of the link positioned to one side of the line of stress between the cable and the bucket hinge and to be unfolded by gravity of the bucket hinge to lower the hinge when the joint of the link has been moved to the other side of the line of stress between the cable and the bucket hinge. 110 115 120

5. An excavating bucket comprising in combination a pair of scoop segments, a bucket hinge for joining the segments so that they may be opened and closed by vertical movement of the hinge, corner bars 125 pivoted at their lower ends to the outer portion of the scoop segments and pivoted together at their upper ends for supporting

the outer portions of the scoop segments, a sheave for operating the bucket hinge, a cable extending around the sheave and secured to the corner bars for supporting the bucket adapted to draw the sheave toward the corner bars to close the bucket, and a folding link connecting the sheave with the bucket hinge adapted, when in folded position, to support the bucket hinge adjacent to the sheave and to be held in folded position by the weight of the bucket, and when in unfolded position to permit the bucket hinge to lower to open the scoop segments, the said folding link being adapted to be unfolded by the weight of the bucket after the link elements have been relatively displaced a predetermined distance.

6. An excavating bucket comprising in combination a pair of scoop segments, a bucket hinge for joining the segments so that they may be opened and closed by vertical movement of the hinge, corner bars pivoted at their lower ends to the outer portion of the scoop segments and pivoted together at their upper ends for supporting the outer portions of the scoop segments, a sheave for operating the bucket hinge, a cable extending around the sheave and secured to the corner bars for supporting the bucket adapted to draw the sheave toward the corner bars to close the bucket, a radius bar pivoted at one end to one of the scoop segments and at the other end to the sheave adapted to hold the lower sheave to one side of the corner bar pivot so as to be accessible from above when the scoop segments are open and supported from beneath when the sheave is in its lowermost position, and a folding link connecting the sheave with the bucket hinge adapted, when in folded position, to support the bucket hinge adjacent the sheave and to be held in folded position by the weight of the bucket, and when in unfolded position to permit the bucket hinge to lower to open the scoop segments, the said folding link being adapted to be unfolded by the weight of the bucket after the link elements have been relatively displaced a predetermined distance.

50 7. An excavating bucket comprising in combination a pair of scoop segments, a hinge for connecting the segments so that they may be opened and closed by substantially vertical movement of the hinge, corner bars pivoted at their lower ends to the outer portion of the scoop segments and pivoted together at their upper ends for supporting the outer portions of the scoop segments, a folding link connected at one end to the hinge and having the other end free and adapted to support the hinge when in folded position and to permit of the opening of the segments when in unfolded position, a sheave pivoted to the free end of the folding link, a radius bar pivoted at one end to a scoop segment and at the other end to the sheave, and an operating cable passing around the sheave and secured to the corner bars adapted to draw the sheave toward the corner bars to close the bucket.

8. An excavating bucket comprising in combination a pair of scoop segments, a hinge for connecting the segments so that they may be opened and closed by substantially vertical movement of the hinge, corner bars pivoted at their lower ends to the outer portion of the scoop segments and pivoted together at their upper ends for supporting the outer portions of the scoop segments, a folding link connected at one end to the hinge and having the other end free and adapted to support the hinge when in folded position and to permit of the opening of the segments when in unfolded position, a sheave pivoted to the free end of the folding link, and an operating cable passing around the sheave and secured to the corner bars adapted to draw the sheave toward the corner bars to close the scoop segments.

9. An excavating bucket comprising in combination a pair of scoop segments, a hinge for connecting the segments so that they may be opened and closed by substantially vertical movement of the hinge, corner bars pivoted at their lower ends to the outer portion of the scoop segments and pivoted together at their upper ends for supporting the outer portions of the scoop segments, a folding link connected at one end to the hinge and having the other end free and adapted to support the hinge when in folded position and to permit of the opening of the segments when in unfolded position, a sheave pivoted to the free end of the folding link, and an operating cable passing around the sheave and secured to the corner bars adapted to draw the sheave toward the corner bars to close the bucket.

10. An excavating bucket comprising in combination a pair of scoop segments, a hinge for connecting the segments so that they may be opened and closed by substantially vertical movement of the hinge, corner bars pivoted at their lower ends to the outer portion of the scoop segments and pivoted together at their upper ends for supporting the outer portions of the scoop segments, a folding link connected at one end to the hinge and having the other end free and adapted to support the hinge when in folded position and to permit of the opening of the segments when in unfolded position, a sheave pivoted to the free end of the folding link, an operating cable passing around the sheave and secured to the corner bars, adapted to draw the sheave toward the corner bars to close the bucket, and a trip member for engaging the folding link to move it into unfolding position to open the scoop segments.

11. An excavating bucket comprising in combination a pair of scoop segments, a hinge for connecting the segments so that they may be opened and closed by substantially vertical movement of the hinge, corner bars pivoted at their lower ends to the outer portion of the scoop segments and pivoted together at their upper ends for supporting the outer portions of the scoop segments, a folding link connected at one end to the hinge and having the other end free and adapted to support the hinge when in folded position and to permit of the opening of the segments when in unfolded position, a sheave pivoted to the free end of the folding link, a radius bar pivoted at one end to a scoop segment and at the other end to the sheave, and an operating cable passing around the sheave and secured to the corner bars.

corner bars, adapted to draw the sheave toward the corner bars to close the bucket.

11. An excavating bucket comprising in combination a pair of scoop segments, a hinge for connecting the segments so that they may be opened and closed by substantially vertical movement of the hinge, corner bars pivoted at their lower ends to the outer portion of the scoop segments and pivoted together at their upper ends for supporting the outer portions of the scoop segments, a folding link connected at one end to the hinge and having the other end free and adapted to support the hinge when in folded position and to permit of the opening of the segments when in unfolded position, a sheave pivoted to the free end of the folding link, an operating cable passing around the sheave and secured to the corner bars, adapted to draw the sheave toward the corner bars to close the bucket, a trip member for engaging the folding link to move it into unfolding position to lower the hinge and open the scoop segments, and a stop carried by the corner bars adapted to limit the upward movement of the sheave when the folding link has been unfolded.

12. An excavating bucket comprising in combination a pair of scoop segments, a bucket hinge for joining the segments so that they may be opened and closed by vertical movement of the hinge, corner bars pivoted at their lower ends to the outer portion of the scoop segments and pivoted together at their upper ends for supporting the outer portions of the scoop segments, an upper sheave pivoted to the corner bars, a lower sheave for operating the bucket hinge, a cable coöperating with the upper and lower sheaves for supporting the bucket adapted to draw the lower sheave toward the upper sheave to close the bucket, and a folding link connecting the lower sheave with the bucket hinge adapted, when folded, to support the bucket hinge adjacent the sheave and to be held in folded position by the weight of the bucket, and when unfolded to permit the bucket hinge to lower to open the scoop segments, the said folding link being adapted to be unfolded by the weight of the bucket after the link elements have been relatively displaced a predetermined distance.

13. An excavating bucket comprising in combination a pair of scoop segments, a bucket hinge for joining the segments so that they may be opened and closed by vertical movement of the hinge, corner bars pivoted at their lower ends to the outer portion of the scoop segments and pivoted together at their upper ends for supporting

the outer portions of the scoop segments, an upper sheave pivoted to the corner bars, a lower sheave for operating the bucket hinge, a cable passing around the upper and lower sheaves and secured to a scoop segment intermediate the outer corner and the hinge thereof for supporting the bucket and adapted to draw the lower sheave toward the upper sheave to close the bucket, and a folding link connecting the lower sheave with the bucket hinge adapted, when folded, to support the bucket hinge adjacent the sheave and to be held in folded position by the weight of the bucket, and when unfolded to permit the bucket hinge to lower to open the scoop segments, the said folding link being adapted to be unfolded by the weight of the bucket after the link elements have been relatively displaced a predetermined distance.

14. In combination, a pair of scoop segments hinged together, corner bars pivoted to the outer portions of the scoop segments and to each other at their upper ends, a support carried by said bars, a folding link connected to the hinge at one end and having the other end free, a connection between said free end and one of the scoop segments, and a lifting cable extending between said free end and the support on said bars, the said folding link being arranged so as to assume a folded position under the influence of gravity when the bucket is supported in open position from beneath and the lifting cable is slackened and to maintain said folded position and cause the closing of the bucket when lifting force is applied to the cable to cause the folded link to approach such support, and further arranged to permit the opening of the segments when the said link is unfolded.

15. In combination, a pair of scoop segments hinged together, corner bars pivoted to the outer portions of the scoop segments and to each other at their upper ends, a support carried by said bars, a folding link connected to the hinge at one end and having the other end free, a connection between said free end and one of the scoop segments, and a lifting cable extending between said free end and the support on said bars, the said folding link being arranged so as to assume a folded position under the influence of gravity when the bucket is supported in closed position from beneath and the lifting cable is slackened, and to be unfolded to cause an opening of the segments when lifting force is applied to the cable.

WILLIAM M. VENABLE.
